(57) **CLAIM**

The ornamental design for an oral care implement, as shown and described.

DESCRIPTION

FIG. 1 is a right front perspective view of an oral care implement according to a first embodiment of the new design;

FIG. 2 is a left front perspective view thereof;

FIG. 3 is a right rear perspective view thereof;

FIG. 4 is a left rear perspective view thereof;

FIG. 5 is a front view thereof;

FIG. 6 is a rear view thereof;

FIG. 7 is a right side view thereof;

FIG. 8 is a left side view thereof;

FIG. 9 is a top view thereof;

FIG. 10 is a bottom view thereof;

FIG. 11 is a right front perspective view of an oral care implement according to a sixth embodiment of the new design;

FIG. 12 is a left front perspective view thereof;

FIG. 13 is a right rear perspective view thereof;

FIG. 14 is a left rear perspective view thereof;

FIG. 15 is a front view thereof;

FIG. 16 is a rear view thereof;

FIG. 17 is a right side view thereof;

FIG. 18 is a left side view thereof;

FIG. 19 is a top view thereof; and,

FIG. 20 is a bottom view thereof.

The stippling indicates a contrast in color, material and/or texture, with no specific color, material and/or texture being claimed.

1 Claim, 10 Drawing Sheets
